LIFTING DEVICE

Alvin L. Johnson, Ottawa Hills, Ohio, assignor to
 The Logan Gear Company, Toledo, Ohio, a corporation of Ohio

Application May 6, 1937, Serial No. 141,140

6 Claims. (Cl. 254—111)

This invention relates to lifting devices and more especially to lifting jacks utilizing dual pawl mechanism for elevating and lowering a lifting element.

5 The invention embraces the provision of simple yet positive acting dual pawl mechanism for manipulating the lifting element and in which the pawls per se may be fabricated from sheet material and configurated to a section having great strength yet utilizing a minimum amount of metal.

An object of the invention is the provision of a lifting jack of this character in which the lifting element may be of circular section but threaded 15 or grooved to provide spaced teeth for cooperation with the pawl mechanism.

Another object of the invention resides in the provision of a sheet metal housing for the mechanism preferably fabricated of one piece of material and so configurated as to form an elongated guiding means for the lifting element and which is reinforced by ribs formed in the walls of the housing lending strength and rigidity to the same.

25 A further object of the invention is the provision of a so-called ratchet jack wherein a major number of the elements of the structure may be fabricated of sheet metal in suitable dies, thus materially reducing the cost of producing the 30 elements of the lifting jack yet enhancing the interchangeability of parts for purposes of replacement or repair should this become necessary.

Further objects and advantages are within the scope of this invention such as relate to the arrangement, operation and function of the related elements of the structure, to various details of construction and to combinations of parts, elements per se, and to economies of manufacture and numerous other features as will be apparent 40 from a consideration of the specification and drawings of a form of the invention, which may be preferred, in which:

Figure 1 is a side elevational view of a form of lifting jack of my invention;

45 Figure 2 is a side elevational view of the upper portion of the lifting jack, part of the housing being broken away and the interior mechanism shown in section for purposes of illustration, this view illustrating the position of the pawl mechanism at one stage during elevation of the lifting element or thrust bar;

Figure 3 is a view similar to Figure 2 showing the position of the pawl mechanism at one stage during the retraction of the lifting element;

50 Figure 4 is a view similar to Figure 3 showing

the pawl mechanism in a different position during retraction of the lifting element;

Figure 5 is a view showing the pawl mechanism and the lifting element in the latter's partially extended position;

5 Figure 6 is a view similar to Figure 5 showing the arrangement for preventing further extension of the lifting element;

Figure 7 is an isometric perspective view illustrating the pawl mechanism and associated parts;

10 Figure 8 is a side elevational view of the housing structure of my invention;

Figure 9 is a sectional view through the housing structure taken substantially on the line 9—9 of Figure 8.

15 While I have illustrated the arrangement of my invention as particularly adapted for use in elevating vehicles and the like, it is to be understood that I contemplate the use of my invention wherever the same may be found to have utility.

20 Referring to the drawings in detail, the arrangement of my invention includes a base member 10 preferably formed of sheet metal having side flanges 11 and end flanges 12 serving to add strength and rigidity to the base member.

25 Mounted upon the base member is a housing or casing structure 14 preferably fabricated of one piece of sheet metal and generally of U-shaped configuration as illustrated in Figure 9. The housing is formed with substantially parallel side wall portions 15 and 16 which are joined together at their bight portions by means of a cylindrical configuration 17, the housing having integrally formed laterally extending flanges 18 and 19 which are rigidly secured to the base member by 30 means of rivets 20 or other suitable securing means.

It is to be noted that the cylindrical configuration 17 continues to a point where portions of the side walls project inwardly as at 21 forming a cylindrical guide for a lifting element. The upper portions of the side walls of housing 14 project laterally in closing the upper part of the housing and these flanges as at 25 are brought together forming at the top of the housing a 40 complete cylinder so that when the lifting element is moved to its uppermost position, it is still restrained against tilting with respect to the housing portion by means of this guide.

The lower portions of the side walls 15 and 16 of the housing are provided with reinforcing ribs 22 and 23 which serve to impart substantial rigidity and strength 45 to the housing structure. The parallel side wall portions of the housing are held in spaced relation by suitable means as, for example, rivets

The cylindrical configuration 17 of the housing structure forms a guiding tubular configuration within which is slidably positioned a thrust bar or rack 26 which may be in the form of a threaded bar, the threads in themselves acting as rack teeth for engagement with pawl mechanism to be hereinafter described for elevating and lowering the thrust bar or lifting element. The upper portion of the thrust bar is provided 10 with a reduced tenon 27 adapted to receive and position a load engaging member 28, the latter being held to the thrust bar by the swaged portion 29 of the tenon 27.

The thrust bar actuating mechanism of my 15 invention comprises a pair of pawls or pawl members 36 and 37, these pawl members being preferably formed of sheet metal to a U-shaped configuration as clearly shown in Figure 7. I have provided a lever member 38 which is preferably 20 formed of sheet metal and having a socket portion 40 adapted to receive an operating handle 41, the lever 38 being preferably formed of one piece of metal, its lower portions being secured together by rivets as at 42 or by other suitable 25 securing means. The lever member 38 is fulcrumed upon a pin or shaft 44 through openings in the spaced parallel wall portions 45 and 46 of the lever member. The side walls of pawl member 36 are provided with openings to also receive 30 pin 44 in which manner the pawl 36 is pivotally supported upon the fulcrum pin for the lever member 38.

The parallel wall portions 45 and 46 are also 35 provided with aligned openings to receive a pin or shaft 47, which also passes through aligned openings in the side walls of pawl 37, thus forming a support for the pawl 37. As hereinafter designated, the pawl 37 will be referred to as the lifting pawl and the pawl 36 referred to as the retaining pawl. As the threads on the bar 26 are 40 spiralled upwardly, in order to effect a full surface engagement of the pawls with the teeth of bar 26, the extremities of the pawls are slanted upwardly substantially the same amount as the 45 degree of spiral in the threads. In this manner the load is transmitted through the bar 26 to the pawls through a substantial pawl engaging surface which also eliminates any tendency of the spiral threads on the bar 26 to tip the pawls.

50 Projecting within the side walls of the pawls 36 and 37 are the leg portions 49 and 50 of a hairpin-like spring 51 of rectangular cross section having its bight portion 52 of cylindrical configuration embracing the lever fulcrum pin 44. Each of the pawl members 36 and 37 are 55 provided with aligned openings 53 and 54 in the side walls thereof to receive cotter keys 55 and 56, the extremities of the leg portions 49 and 50 of the spring projecting respectively between the 60 leg portions of the cotter keys 55 and 56 as particularly illustrated in Figure 7.

Lever member 38 is also provided with a pin 61 which carries a spring 62 preferably formed of wire having its bight portion 63 contacting 65 with the rear edges of the parallel wall portions of pawl 36 as illustrated in Figure 7 while the free extremities of the spring engage with an edge portion 63' of the lever member 38, the spring being so formed as to exert a counter-clockwise pressure against the pawl 36 as shown 70 in Figure 6.

Arranged between the parallel wall portions of 75 lever 38 is a member 64 of U-shaped configuration having its parallel side wall portions formed to embrace the cylindrical bight portion 52 of

spring 51 whereby it is thus indirectly supported by the fulcrum pin 44. The member 64 is provided with depending ledge portions 66 and 67. Suitably fulcrumed upon a pivot pin 68 carried by one wall of the housing 16 is a control dog or 5 member 70 having its upper extremity arranged for cooperative relation with the depending ledge portions 66 and 67 for a purpose hereinafter explained, the depending arm of the control dog 70 having a manipulating button 72 projecting 10 exteriorly of the casing and carried by a laterally projecting portion 73 of dog 70, the projecting portion extending through a slot 74 formed in the side wall of the housing permitting the control dog 70 to be oscillated about its pivot point 15 through the medium of the manipulating button 72. The manipulation of the control button acting to move the control dog 70, the latter arranged to shift the member 64, serves as a means 20 for changing the action of the pawls to elevate or retract the thrust bar 26 in a manner to be hereinafter described.

It is to be noted that the lower extremity of the thrust bar or lifting element 26 carries a member 76 swaged thereto as at 77 having a 25 laterally projecting portion arranged to engage the bight portion of pawl 37 when the thrust bar has been elevated to its uppermost position as illustrated in Figure 6 to prevent the thrust bar from moving upwardly beyond a predetermined 30 point as the member 76 prevents further reengagement of the pawl 37 with the thrust bar.

The operation of the structure is as follows: Referring particularly to Figures 2, 5 and 6, there are illustrated various stages or positions of the 35 pawl mechanism during the sequence of movements of the mechanism while the lifting element is being elevated. In Figure 2 the actuating lever member 38 is in its extreme counter-clockwise position of oscillation about the fulcrum 44 in which position pawl 37 is urged into engagement with a tooth of the thrust bar 26 under the influence of the branch 50 of the hairpin spring 51, both leg portions of the spring 51 being urged toward the thrust bar 26 under 40 the influence of member 64, the latter being held in the position shown in Figure 2 by the control dog 70, the button 72 being illustrated in the "up" position. After the pawl 37 has engaged a tooth of the thrust bar, the handle 38 is oscillated by the operator about its fulcrum 44 in a clockwise direction, as viewed in the drawings, which elevates the thrust bar and the elevating pawl 37 until the retaining pawl 36 under the counter-clockwise influence of the portion 49 of the spring 51 falls into a recess between the teeth in the thrust bar 36. After pawl 36 is in a position projecting beneath one of the teeth of thrust bar 26, movement of the handle member 38 in a counter-clockwise direction moves the lifting 50 pawl 37 out of engagement with a tooth of the thrust bar, the latter being retained in its elevated position by the retaining pawl 36. The oscillation of handle member 38 then lowers the lifting pawl 37 to engage the next successive 55 tooth in the thrust bar or rack 26 and the elevating operation repeated as above set forth. With the control button located in the "up" position, as illustrated in Figure 2, repeated oscillation of the lever member 38 continues to elevate the 60 thrust bar 26 until such time as the member 76 is brought into contact with the bight portion 80 of the lifting pawl 37 as particularly shown in Figure 5, the curved portion 81 at the rear of the pawl serving as a cam means engaging with 65

75

the bight portion 82 of the retaining pawl 36 preventing the latter from reengagement with any tooth of the rack member when the handle 38 is oscillated in a clockwise direction as shown in Figure 5.

When further effort is made to elevate the jack with the thrust bar in this position, the handle member is moved in a clockwise direction to the position shown in Figure 6 in which position the retaining pawl 36 is supporting the load by engagement with a tooth in the thrust bar while the member 76 slides along the face of the cam surface 80 preventing the lifting pawl 37 from engaging a tooth in the thrust bar. By this means, a further elevation of the rack or thrust bar is prevented.

When it is desired to retract the lifting element and lower the load with which the same may be in engagement, the control button 72 is manipulated to the "down" position as illustrated in Figure 3, which movement of button 72 swings the control dog 78 to the position illustrated in Figure 3. This movement of the dog 70 shifts the member 64 to distort the spring 51 so that the resiliency of the leg portions thereof tends to withdraw the pawls from engagement with the bar 26. In the position shown in Figure 3, the weight of the load is carried upon the pawl 36, and the pawl 37 has been retracted from engagement with the rack under the influence of leg 50 of spring 51. The oscillation of the handle member 38 in a clockwise direction elevates the pawl 37 and by reason of the cam face 82 of pawl 36 engaging the rear portion 81 of pawl 37, the latter is cammed into a position beneath one of the teeth of the thrust bar 26 and slightly further clockwise oscillation of the handle 38 causes the load to be supported upon the pawl 37 slightly elevating the rack bar 26, relieving the stress of the load upon pawl 36 so that the latter is disengaged and swings away from the bar 26 under the influence of the leg 49 of spring 51. Counterclockwise oscillation of lever 38 about its fulcrum lowers the rack bar, as the latter is then carried upon the pawl 37. As the lever 38 approaches its maximum counter-clockwise position, spring 90 which bears against the rear portion of pawl 36 and acts in opposition to the leg 49 of spring 51 overcomes the resiliency of the spring portion 49 and urges the extremity of pawl 36 into engagement with the next succeeding tooth on the rack bar so that the pawl 36 then carries the load. The lever is again moved in a clockwise direction and the pawl 37 is again cammed into engagement with a tooth in the lifting element so as to carry the load permitting the pawl 36 to be withdrawn by the spring 49 from engagement with the rack. This oscillating action of the handle member 38 may be continued and with each oscillation the rack is lowered the distance of one tooth of the rack bar until the lifting element is at its lowermost position.

It is apparent that within the scope of the invention, modifications and different arrangements may be made other than are herein disclosed, and the present disclosure is illustrative merely, the invention comprehending all variations thereof.

What I claim is:

1. A lifting device including a base member; a housing, said housing having a tubular guide portion; a toothed lifting element reciprocably carried in said guide portion; a load engaging element carried by said toothed lifting element; a lever fulcrumed upon said housing; a lifting pawl

pivottally supported upon said lever; a retaining pawl pivotally carried on the fulcrum of said lever, said pawls being formed of sheet metal to substantial U-shaped configuration; a plate spring of U-shaped configuration having its bight portion embracing the fulcrum of said lever and the leg portions thereof operatively connected to said pawls between their parallel wall portions; and a member carried on the fulcrum of said lever and having portions cooperating with said spring for changing the effect of said spring upon said pawls. 5

2. A lifting device including a base member; a housing, said housing having a tubular guide portion; a toothed lifting element reciprocably carried in said guide portion; a load engaging element carried by said toothed lifting element; a lever fulcrumed upon said housing; a lifting pawl pivotally supported upon said lever; a retaining pawl pivotally carried on the fulcrum of said lever, said pawls being formed of sheet metal to substantial U-shaped configuration; a hairpin spring embracing the fulcrum of said lever and having the leg portions thereof cooperating respectively with said pawls; a member for 20 retaining said spring in contact with the fulcrum of said lever and having portions cooperating with said spring for changing the effect of said spring upon said pawls; a dog; and manipulating means carried by said dog for shifting the latter 30 to change the position of said member.

3. A lifting device comprising, in combination, a base member; a housing formed of one piece of sheet metal; said housing being formed with a tubular guide portion; a threaded lifting element 35 reciprocably contained in the tubular guide portion of said housing; a lever fulcrumed upon said housing; a lifting pawl; a retaining pawl, said pawls having cooperative connection with said lever; a spring embracing the fulcrum of said 40 lever and having its leg portions respectively connected to said pawls; means for controlling the action of said spring upon said pawls; and means carried by said lifting element and engageable with one of said pawls urging the pawl away 45 from the lifting element when the same is elevated to its full extended position.

4. A lifting device comprising, in combination, a base member; a housing formed of one piece of sheet metal and arranged in substantially U- 50 shaped configuration, the bight portion of said housing being tubular; a toothed lifting element reciprocably contained in the tubular portion of said housing; a lever fulcrumed upon said housing; a lifting pawl; a retaining pawl, said pawls 55 having cooperative association with said lever; a U-shaped spring embracing the fulcrum of said lever and having its leg portions respectively connected to said pawls; a second spring having engagement with the retaining pawl opposing the 60 action of the U-shaped spring when the lifting element is being retracted; means for controlling the action of said U-shaped spring upon said pawls; and means carried by said lifting element and engageable with one of said pawls when the 65 lifting element is elevated to its full extended position.

5. A lifting device comprising, in combination, a base member formed of sheet metal; a one piece sheet metal housing secured to said base 70 member, said housing having a tubular guide portion and spaced parallel wall portions, said wall portions having reinforcing ribs formed therein; means securing said wall portions together and in spaced relation; a toothed lifting 75

element reciprocably mounted in said guide portion; a lever fulcrumed on said housing; a lifting pawl and a retaining pawl cooperatively associated with said lever; a U-shaped spring having its leg portions respectively in cooperative engagement with each of said pawls; and control means for changing the action of said spring upon said pawls including a member carried upon the fulcrum of said lever and embracing the bight portion of said spring.

6. A lifting device including a base member; a housing, and housing having a tubular guide portion; a toothed lifting element reciprocably carried in said guide portion; a load engaging

member carried by said toothed lifting element; a lever fulcrumed upon said housing; a pair of pawls formed of sheet metal; said pawls being cooperatively associated with said lever; a spring having a portion embracing the fulcrum of said lever and having connection with each of said pawls; a control member for retaining said spring portion in contact with the fulcrum of said lever and for changing the effect of said spring upon said pawls; and means cooperating with said control member for changing the effective action of said spring on said pawls.

ALVIN L. JOHNSON.
